ABSTRACT

A sensor including a pick-up panel having photosensitive transistors whose emitters are connected to column conductors and whose collectors are connected to row conductors. The row conductors are connected to emitters of row selection transistors whose bases are connected to outputs of a row scanning generator and whose interconnected collectors are connected to an output circuit. The column conductors are directly connected to a column scanning generator. The influence of parasitic capacitances is eliminated by causing the output circuit to provide a constant voltage, by always impressing voltage on the column conductors and by switching over the row selection transistors in a signal blanking period.

SENSOR PROVIDED WITH A PICK-UP PANEL

The invention relates to a sensor provided with a pick-up panel formed with a cross-bar system of row and column conductors and pick-up elements occurring between intersections, said conductors being connected to outputs of row and column scanning generators each applying successive pulses with a reference voltage to the outputs, said panel being connected to an output circuit for applying an output signal to an output of the sensor through a row and column selection, the outputs of the row-scanning generator being connected to bases of transistors whose emitters are each connected to a row conductor.

A sensor of this kind has been described in an Article in the "I.E.E.E. Journal of Solid-State Circuits" of December 1969, on pages 326 to 333. Fields of application of the sensor formed with photosensitive pick-up elements may be, for example, television cameras, optical readers for computers and character recognition devices.

It has been stated that the output circuit is coupled to the column conductors and this through a number of transistors which are each formed with an insulated gate electrode, such as field-effect transistors. The transistors in the output circuit are alternatively rendered conducting by pulses applied by the column scanning generator to the gate electrodes.

The Article states that a locally strong exposure causes a considerable cross-over to proximate pick-up elements.

Furthermore, when using the field-effect transistors operating as switches in the output circuit, these transistors each have a considerable resistance in their conducting condition, which resistances mutually have a given spread. When reproducing the output signal provided by the sensor the spread in these resistances becomes manifest as stripes located in the column or vertical direction.

The use of bipolar photo transistors in the pickup panel and field effect transistors in the output circuit requires two different technologies in case of a structure in one and the same semiconductor body, which is a drawback for the value of the output because the number of process stages is increased.

In the desired embodiment of the sensor crossover phenomena between the various pick-up elements caused by parasitic couplings and capacitances occur to a more or less strong extent in the output signal and transient phenomena caused by the row and column selection are disturbingly noticeable.

An object of the invention is to realize a sensor in which the disturbing transient phenomena and crossover are reduced to a strong extent in the output signal and to this end the sensor according to the invention is characterized in that the interconnected collectors of the said transistors connected to the row scanning generator are connected to the output circuit.

A further reduction of interference is possible in a sensor provided with pick-up elements formed with a photosensitive transistor whose emitter is connected to one of the column conductors and whose collector is connected to one of the row conductors, and which is characterized in that the outputs of the column scanning generator convey a determined voltage cutting off the said transistors in the temporary absence of the said pulse with the reference voltage.

A further reduction of interference is possible in a sensor which is characterized in that the said interconnected collectors are connected to an emitter of at least one transistor present in the output circuit, the base of said transistor being connected to a bias source and its collector being coupled to the output of the sensor.

The proposed structure of the sensor eliminates the influence of parasitic capacitances. This is the case for the row conductors by maintaining the voltage across the row conductor through the said transistor connected thereto constant in a selected row employing high frequency switching between the columns, and as regards the column conductors, by impressing a voltage on these conductors even when the pulse with the reference potential is absent; none of the column conductors may be free. A further elimination is realized by causing the transistor in the output circuit to apply a constant voltage to the interconnected collectors of the transistors being connected to the row conductors and bringing about the low-frequency switching between the row conductors. Due to the said steps cross-over and transient phenomena no longer occur disturbingly noticeable in the output signal of the sensor.

The invention will be described in greater detail with reference to the following Figures as examples in which:

FIG. 1 shows a switching circuit diagram of a sensor according to the invention,

FIG. 2 shows a second embodiment of an output circuit suitable for this sensor according to the invention, and

FIGS. 3a and 3d show the structure of a pick-up panel present in the sensor according to FIG. 1 in a semiconductor body.

In the sensor shown in FIG. 1 according to the invention row and column conductors constituting a cross-bar system are successively denoted by $A_{10}, A_{20}, A_{30}, \dots A_{10}$ and $A_{01}, A_{02}, A_{03}, \dots A_{0X}$. The references A_{01}, A_{02}, A_{03} and A_{0X} not only denote the column conductors but also the signals which they convey as they are connected to outputs of a column scanning generator denoted by G_x . The row conductors A_{10}, A_{20}, A_{30} and A_{10} are connected to emitters of transistors T_{10}, T_{20}, T_{30} and T_{10} , respectively, whose bases are connected through connections with some signals shown A_{11}, A_{21}, A_{31} and A_{Y1} to outputs of a row scanning generator G_y .

To obtain a coupling between the instants when the said signals $A_{11} \dots A_{Y1}$ and $A_{01} \dots A_{0X}$ occur there has been shown that a synchronizing signal S is applied to the generators G_y and G_x . The signal S may be, for example, a television synchronizing signal. X denotes the number of image spots constituting a television line and Y is the number of lines constituting a television image. Interlacing is possible in this case.

The collectors of the transistors $T_{10}, T_{20} \dots T_{Y0}$ are connected together and are connected through an output conductor A_{00} to an input Z_0 of an output circuit Z and are connected therein to the emitters of two transistors T_1 and T_2 . The bases of the transistors T_1 and T_2 are connected to two outputs of a voltage source W_1 . The synchronizing signal S is applied to the source W_1 and under its control the source W_1 provides a voltage M_1 and M_1 which is composed of a bias having a value of $+U_1$ and a square-wave varying alternating voltage. The square-wave alternating voltage occurs in the voltages M_1 and M_1 in phase opposition and the result is

that the transistors T_1 and T_2 are alternately conducting and cut off.

Furthermore the output circuit Z is provided with a second voltage source W_2 synchronized by the signal S and providing voltages M_2 and M_2 . It has been shown for the voltages M_2 and M_2 that they have a square-wave variation in phase opposition between the values of $+U_2$ and $+U_3$. The voltage M_2 is applied to the anode of a diode D_1 whose cathode is connected to the collector of the transistor T_1 . The connection point of the diode D_1 and the transistor T_1 denoted by Z_1 is connected through a capacitor C_1 and in parallel therewith a series arrangement of a diode D_2 and a resistor R_1 to a connection which conveys a direct voltage of the value $+U_3$. In the same manner the output of the source W_2 conveying the voltage M_2 is connected through a diode D_3 to the collector of the transistor T_2 and a connection point Z_2 thus formed is connected through a capacitor C_2 and a diode D_4 in series with the resistor R_1 to the connection conveying the direct voltage $+U_3$. The direct voltage $+U_3$ may be derived in a manner not shown from a supply source connected to ground which, for example, also feeds the source W_2 . The junction of the resistor R_1 and the diodes D_2 and D_4 is connected to an output of the sensor according to FIG. 1 denoted by Z_3 .

To explain the operation of the output circuit Z the following applies. It is assumed that the points Z_1 and Z_2 both convey a voltage which is equal to the voltage $+U_3$ minus a diode threshold voltage U_D which occurs, inter alia, across the diodes $D_1 \dots D_4$. The voltage $+U_3$ occurs at the output Z_3 . It is found from the voltages M_1 and M_1 shown in FIG. 1 that in case of cyclical operation always one of the transistors T_1 and T_2 conducts and the other is cut off while it follows from the voltages M_2 and M_2 that the same applies to the diodes D_3 and D_1 . When the transistor T_1 becomes conducting at an instant t_0 denoted for the voltage M_1 at which the diode D_1 is blocked and when the input Z_0 takes up some current during a short period, it is derived through the transistor T_1 from the capacitor C_1 . The voltage at point Z_1 thereby decreases while a negligible leakage current flows through the resistor R_1 and the diode D_2 to the point Z_1 . The voltage drop across point Z_1 likewise occurs at the output Z_3 .

Subsequently the transistor T_1 and the diode D_3 are blocked at an instant t_1 under the control of the voltages M_1 and M_2 and under the influence of the voltages M_1 and M_2 the transistor T_2 and the diode D_1 become conducting. The source W_2 applies the voltage $+U_3$ to the diode D_1 so that the voltage at point Z_1 immediately increases to the voltage $+U_3 - U_D$ while the voltage U_D occurs across the diode D_1 . The output Z_3 would thereby start to convey the voltage $+U_3$ if it were not for the input Z_0 taking up some current in a short time in case of the conducting state of the transistor T_2 , which current, derived from the capacitor C_2 , causes the voltage at point Z_2 and hence at the output Z_3 to decrease.

When subsequently the transistor T_1 and the diode D_3 become conducting at an instant t_2 , described effect is repeated.

Two important points for the output circuit Z are the following:

Since either transistor T_1 or transistor T_2 always conducts, the input Z_0 conveys a more or less constant voltage $+U_4$. When, for example, there applies that the

voltage $+U_1$ is equal to $+5V$, the voltage M_1 varies between 5 ± 0.3 V and the base-emitter voltage drop which is as large as the voltage U_D is equal to 0.7 V, the input Z_0 conveys a voltage $U_4 = 4.6$ V. The source W_1 is then active as a bias source for the conducting transistor T_1 or T_2 .

Together with the transistor T_1 and through the diode D_1 with the source W_2 , the capacitor C_1 constitutes an integrator (C_1 , T_1 , W_2). The source W_2 is active with the voltage $+U_3$ as a reference voltage source. Relative to the voltage $+U_3 - U_D$ at which the voltage U_D occurs across the diode D_1 , the connection point Z_1 has a voltage drop which is given by the current occurring at the input Z_0 and being integrated by capacitor C_1 . In this case the maximum voltage drop given by the integrated current must not exceed the value $(U_3 - U_2)$ because otherwise the diode D_1 may start to conduct in an unwanted manner in case of the transistor T_1 conducting. In the same manner the capacitor C_2 , the transistor T_2 and the source W_2 connected thereto through the diode D_3 constitute a second integrator (C_2 , T_2 , W_2). For the given voltages there may apply that reference voltage $U_3 = 10V$ and that voltage U_2 is approximately equal to 7V.

The advantages of the output circuit Z are apparent from the further description of the pick-up panel connected to the input Z_0 with pick-up elements TC occurring between intersections. npn-transistors $T_{11} \dots T_{YX}$ are connected to the intersections between the row conductors $A_{10} \dots Y_{Y0}$ and the column conductors $A_{01} \dots A_{0X}$. The collector of each of the transistor $T_{11} \dots T_{YX}$ is connected to one of the row conductors $A_{10} \dots A_{Y0}$ and the emitter is connected to one of the column conductors $A_{01} \dots A_{0X}$. The transistors $T_{11} \dots T_{1X}$; $T_{21} \dots T_{2X}$; $T_{Y1} \dots T_{YX}$ constitute rows and the transistors $T_{11} \dots T_{Y1}$; $T_{12} \dots T_{Y2}$; $T_{11} \dots T_{YX}$ constitute columns. The bases of the transistors $T_{11} \dots T_{YX}$ are connected through capacitors $C_{11} \dots C_{YX}$ to the collectors and are further not connected. The capacitors $C_{11} \dots C_{YX}$ may be, for example, capacitors having a photosensitive dielectric, but in a practical form they will be given by the photosensitive base-collector junction occurring in the transistors $T_{11} \dots T_{YX}$ and being in a cut-off condition.

The row and column conductors $A_{10} \dots A_{Y0}$ and $A_{01} \dots A_{0X}$ have parasitic capacitances occurring mutually and to ground which are distributed along the conductors but are indicated in FIG. 1 by a single capacitor $C_{10} \dots C_{Y0}$ and $C_{01} \dots C_{0X}$ to ground. The output conductor A_{00} also has a distributed parasitic capacitance which is indicated by a capacitor C_{00} to ground. In the sensor according to the invention the parasitic capacitances $C_{10} \dots C_{Y0}$, $C_{01} \dots C_{0X}$ and the capacitor C_{00} which normally cause an interference in the form of transient phenomena and cross-over in the output signal of the pick-up panel will not cause only interference.

To explain the operation of the sensor according to FIG. 1 it is assumed that the capacitors $C_{11} \dots C_{YX}$ constituted by the cut off base-collector junction in the transistors $T_{11} \dots T_{YX}$ are irradiated by light after having been charged to a reference voltage to be described hereinafter. The photons of the light produce hole-electron pairs in the semiconductors layers of the transistor $T_{11} \dots T_{YX}$. Dependent on the intensity of the local exposure the hole-electron pairs generated near the base-collector junction discharge the capacitors $C_{11} \dots C_{YX}$.

... C_{YX} occurring at that area. At an instant t_3 shown in FIG. 1 the following applies: it has been stated for the signal A_{11} that at the instant t_3 the base of the transistor T_{10} provides a voltage $+U_5$ while it is apparent from the signals A_2 and A_{Y1} that the bases of the transistors $T_{20} \dots T_{Y0}$ have a voltage U_0 . The voltage U_0 may be the ground potential, hence $U_0 = 0V$. It is found from the signals $A_{01} \dots A_{0X}$ for the column conductors that at the instant t_3 a voltage $+U_6$ occurs across the column conductors. For, for example, $U_5 = 3.7V$ and $U_6 = 3V$ none of the transistors $T_{11} \dots T_{1X}$ can conduct. At the instant t_3 a pulse with $U_0 = 0V$ lasting until the instant t_4 occurs in the signal A_{01} . The result is that with $0V$ across the column conductor A_{01} and $U_5 = 3.7V$ across the connection A_{11} the transistors T_{10} and T_{11} become conducting. The capacitor C_{11} , for example partly discharged by the photons is quickly charged through the collector-emitter path of the transistor T_{10} until the condition is achieved at which the capacitor C_{11} has a voltage of U_5 minus the base-emitter voltage drops of the transistors T_{10} and T_{11} , that is to say, up to $U_5 - 2U_D = 2.3V$. The charge required therefor is derived through the transistor T_2 controlled by the voltage M_1 from the capacitor C_2 . When, for example, the capacitor C_{11} is discharged by the photons with $2V$ and when there applies that $C_{11} = 1.4 \text{ pF}$ while for a current amplification factor β of the transistor T_{11} there applies that $\beta = 100$, a charge of approximately $2 \times 1.4 \times 100 \text{ picocoulomb}$ is transported through the transistor T_{10} . For a value of the capacitor $C_2 = C_1 = 100 \text{ pF}$ it follows that the voltage across the capacitor C_2 becomes $2.8V$. As a result the voltage at the output Z_3 of the sensor decreases from $U_3 = 10V$ to $10 - 2.8 = 7.2V$. This voltage of $2.8V$ occurs, for example, in case of a maximum exposure of the capacitor C_{11} .

The charge transport to the capacitor C_{11} is effected very quickly because the resistance is negligible in the charge circuit with the capacitor C_2 , the transistors T_2 , T_{10} and T_{11} and the conductor A_{01} . When the capacitor C_{11} has been charged to substantially the reference voltage with the value $2.3V$, the transistors T_2 and T_{10} which are capable of remaining conducting under the influence of the voltages across the bases will convey a very low current until the instant t_4 at which the reference voltage is approximated up to a few millivolts.

At the instant t_4 the pulse in the signal A_{01} ends and a pulse in the signal A_{02} commences. The transistor T_2 is then cut off under the control of the voltage M_1 , while the voltage M_1 renders the transistor T_1 conducting. The result is that the capacitor C_{12} is switched in a charge circuit which comprises the capacitor C_1 , the transistors T_1 , T_{10} and T_{12} and the column conductor A_{02} . In the manner described a voltage drop occurs at the output Z_3 which drop is determined by the discharge of the capacitor C_{12} effected therebefore. Simultaneously the voltage source W_2 provides the reference voltage $U_3 - U_D$ through the diode D_3 for the connection point Z_2 . When subsequently at an instant t_5 a pulse occurs in the signal A_{03} while that in the signal A_{02} drops out, the charge across the capacitor C_{13} is implemented from the capacitor C_2 .

For the last transistor T_{1X} in the first row of transistors $T_{11} \dots T_{1X}$ FIG. 1 shows that the capacitor C_{1X} at an instant t_6 is connected through the transistor T_1 to the capacitor C_1 . At an instant t_7 not only the pulse in the signal A_{0X} ends, but also that in the signal A_{11} , while in the signal A_{21} a pulse commences. At an instant t_8 a

pulse in the signal A_{01} commences so that the first capacitor C_{21} in the second row of transistors $T_{21} \dots T_{2X}$ is connected through the transistor T_2 to the capacitor C_2 . Successively, the capacitors $C_{22} \dots C_{2X}$ are connected to the output circuit Z . It has been indicated for the signal A_{Y1} that at the instant t_1 the pulse ends while it follows from the signal A_{0X} that the capacitor C_{YX} is connected to the output circuit Z at the instant t_0 therefore. Subsequently the next cycle of the successive connection of the capacitors $C_{11} \dots C_{YX}$ to the output circuit Z begins at the instant t_3 via the row and column selection with the signals $A_{11} \dots A_{Y1}$ with the reference voltage $+U_5$ and the signals $A_{01} \dots A_{0X}$ with the ground potential U_0 as a reference.

In the description of the operation of the sensor according to FIG. 1 a signal blanking period such as the line and field blanking periods commonly used in television has been taken into account. During the blanking periods there is no video signal information and interferences in the output signal normally caused by the signal generation during these periods are later removed therefrom by clamping circuits. It has been indicated for FIG. 1 that after the switch-over at the instant t_7 of the first row conductor A_{10} to the second row conductor A_{20} the pulse in the signal A_{01} does not occur immediately, but at the instant t_9 . The time between the instants t_7 and t_9 may be considered as a line blanking period. For the sake of simplicity a duration is taken in this case in which otherwise two of the row capacitors $C_{11} \dots C_{1X}$ would have been read out. In practice the line blanking period is approximately 18% of the line period. In the same manner a field blanking period follows because at the instant t_1 the pulse in the signal A_{11} commences and that in the signal A_{01} commences at the instant t_3 . In practice the field blanking period amounts to some 20 line periods.

In the sensor according to FIG. 1 the instants t_1 to t_3 , t_7 to t_9 , etc. have been used in a favourable manner. Since during these instants transient phenomena may occur in the signal at the output Z_3 , they are introduced therein deliberately, while the special structure of the sensor according to FIG. 1 ensures that transient phenomena do not occur outside the blanking periods. This has been achieved by connecting each of the row conductors $A_{10} \dots A_{Y0}$ through the emitter of one of the transistors $T_{10} \dots T_{Y0}$ to the interconnected collectors connected to the output circuit Z , while during the period when the column selection is successively effected the transistor (for example T_{20}) of the selected row conductor (A_{20}) has the reference voltage $+U_5$ at its base. The influence of the parasitic capacitor (C_{20}) which might give interfering transient phenomena in case of the high-frequency column selection is eliminated thereby. In fact, at the commencement of the row selection the free parasitic capacitor (C_{20}) is brought to the reference voltage $U_5 - U_D$ during the signal blanking period (t_7 to t_9) and the transient phenomenon caused thereby in the signal at the output Z_3 occurs in the manner admitted. Subsequently the transistor (T_{20}) remains conducting during the entire period of the subsequent column selections and it maintains the row conductor (A_{20}) and hence the parasitic capacitor (C_{20}) at the voltage $U_5 - U_D$. The selected transistor (T_{20}) conveys a pulsatorily varying current under the influence of the column selection.

For the purpose of illustration there applies that the capacitors $C_{10} \dots C_{Y0}$ have a value of, for example, X

times 0.5 pF for a construction to be further described with reference to FIG. 3 of the pick-up panel according to FIG. 1 integrated in a semiconductor body.

A further reduction of interference is obtained by causing none of the column conductors $A_{01} \dots A_{0X}$ to be free in the described embodiment of the pick-up elements TC with photosensitive, bipolar transistors, but by always impressing a voltage on all column conductors. The voltage $U_6 = 3V$ across all column conductors $A_{01} \dots A_{0X}$ but one ensures that relative to the row conductors $A_{10} \dots A_{Y0}$, all but one of which are free, the base-emitter junctions of the part of the transistors $T_{11} \dots T_{YX}$ present are cutoff under all circumstances. A simple reliable column selection has been obtained by using the base-emitter junctions of the transistors $T_{11} \dots T_X$ when switching over between the columns.

For a pick-up element, for example (T_{22}, C_{22}) the following might be effected in case of a free row conductor A_{20} and column conductor A_{02} . The capacitor C_{22} charged to the reference voltage of 2.3 V which represents the cut-off base-collector junction of the npn transistor T_{22} is discharged by the local exposure with its photon generated hole-electron pairs. Particularly the electrons generated in the n-collector and the holes generated in the p-base are of importance. In case of a strong local exposure, the base-collector junction may be completely discharged and is therefore no longer cut off. A further exposure continues to generate hole-electron pairs with its photons while subsequently the collector becomes active as an emitter. The transistor T_{22} therefore becomes active in an inverse manner. A negative voltage is present across the column conductor A_{02} and the parasitic capacitor C_{02} due to a leakage current flowing through the likewise photosensitive capacitor C_{20} . The result is that the negative voltage across the column conductor A_{02} produced by the transistor T_{22} gives an incorrect column selection at the wrong instant. This has been prevented in the sensor according to FIG. 1 by giving the non-selected conductors of the column conductors $A_{01} \dots A_{0X}$ the voltage $+U_6$ so that the column conductors $A_{01} \dots A_{0X}$ have a defined voltage. The free location of the row conductors $A_{10} \dots A_{Y0}$ which are not selected does not present any problems because in the manner described the transient phenomena are admissible within the signal blanking period.

The voltage $+U_6$ on the non-selected conductors of the column conductors $A_{01} \dots A_{0X}$ not only provides the described advantage but also the advantage that capacitors not shown which occur between the base and the emitter of the transistors $T_{11} \dots T_{YX}$ and which may have a value of, for example, 0.4 pF do not cause any cross-over.

For the purpose of illustration there applies that the capacitors $C_{01} \dots C_{0X}$ have a value of, for example, Y times 0.4 pF in the construction of the sensor to be described with reference to FIG. 3.

A still further reduction of interference is realized by the specific structure of the output circuit Z of the sensor according to FIG. 1. In the output conductor A_{00} which is constituted by the interconnected collectors of the transistors $T_{10} \dots T_{Y0}$, the parasitic capacitor C_{00} is shown. The capacitor C_{00} does not have interfering influences because, as described with reference to the output circuit Z, the voltage $+U_4$ is present at the output conductor A_{00} .

For the purpose of illustration there applies that the capacitor C_{00} has a value of, for example Y times 0.7 pF in the embodiment of the sensor to be described with reference to FIG. 3.

The simplest embodiment of the output circuit Z while maintaining the advantages as described with reference to the possible interference reductions would be an embodiment using one transistor, for example, T_1 whose base is connected to a bias source providing a constant voltage while the collector is directly connected through a resistor, for example, R_1 to the connection with the (reference) voltage $+U_3$. The output Z_3 connected to the connection point of the transistor (T_1) and the resistor (R_1) would convey output pulses under the influence of the current peaks through the transistors $T_{10} \dots T_{Y0}$ which peaks would occur from the voltage $+U_3$. A drawback of this embodiment is that the leading edge of the output pulses which is determined by the resistor occurring in the charge circuit (R_1, T_1 , etc) of the pick-up elements TC is different for the different pick-up elements TC. The pick-up element (T_1, C_{11}) , reckoned up to the input Z_0 has a different charge resistance than the farther remote pick-up element (T_{YX}, C_{YX}) . This has the drawback that the pulse amplitude obtained in the output signal is not a measure for the incident light, but the integrated pulse is.

Due to the said drawbacks a better embodiment of the output circuit Z is the one in which an integrator is used. Thus, for example, the capacitor C_1 connected in parallel with the resistor R_1 might be connected in series with the only transistor T_1 present. The current peaks caused by the pick-up elements TC occur in an integrated form at the output Z_3 . A drawback is that the resistor R_1 is to have a low value so as to ensure that at the end of the short period when a pick-up element TC is read out through the row and column selection the capacitor C_1 is discharged through the resistor R_1 and is thus ready for the next pick-up element TC. The discharge time constant $R_1 C_1$ is to be short relative to the selection period. On the other hand it is, however, desirable that the discharge time constant $R_1 C_1$ is very long so as to obtain a satisfactory integration.

An improvement is the embodiment of the output circuit Z shown in FIG. 1, which comprises two integrators (C_1, T_1, W_2) and (C_2, T_2, W_2) whose capacitors C_1 and C_2 are connected through the transistors T_1 and T_2 alternatively to successive pick-up elements TC. The resistor R_1 only serves for making the output signal available. The slope of the leading edge of the pulsatory output signal is dependent on the resistor in the charge circuit. For the case where such a slope variation is undesirable the embodiment of the output circuit Z shown in FIG. 2 may be used.

In the output circuit Z according to FIG. 2 the output conductor A_{00} connected to the input Z_0 of the pickup panel described with reference to FIG. 1 is connected to the emitters of three transistors T_3, T_4 and T_5 . The collectors of the transistors T_3, T_4 and T_5 are each connected to a terminal of a capacitor C_3, C_4 and C_5 , respectively, the other terminal of which is connected to ground. The junction of the capacitor C_3 and the transistor T_3 is connected to a cathode of a diode D_5 and to a gate electrode of a field effect transistor T_6 . Likewise the transistors T_4 and T_5 are connected to diodes D_6 and D_7 , respectively and to field effect transistors T_7 and T_8 . The interconnected drain electrodes of the

transistors T_6 , T_7 and T_8 are connected through a resistor R_2 to a connection conveying a voltage $+U_7$ and are directly connected to the output Z_3 . The anode of the diode D_5 is connected directly, that of the diode D_7 is connected through a delay circuit E_1 and that of the diode D_6 is connected through a second delay E_2 to an output of a voltage source W_3 . The base of the transistor T_4 is connected directly, that of the transistor T_3 is connected through a delay circuit E_3 and that of the transistor T_5 is connected through a second delay circuit E_4 to an output of a voltage source W_4 . The source electrode of the field effect transistor T_8 is connected through a resistor R_3 to the output of a voltage source W_5 . The source W_5 is furthermore connected through a delay circuit E_5 and a resistor R_4 to the source electrode of the field effect transistor T_7 . The connection point of the delay circuit E_5 and the resistor R_4 is connected through a delay circuit E_6 and a resistor R_5 to the source electrode of the transistor T_6 . The voltage sources W_3 , W_4 and W_5 provide de voltages M_3 , M_4 and M_5 at the outputs under the control of the synchronizing signal S applied thereto. The voltages M_3 , M_4 and M_5 have a pulsatory variation relative to a mean value of $+U_8$, $+U_9$ and $+U_{10}$, respectively. For the pulsatory variations there applies, for example, that M_3 : U_8 ($= 0.5$ V) ± 1.5 V, M_4 : U_9 ($= 5$ V) ± 0.3 V and M_5 : U_{10} ($= 7.5$ V) ± 1.5 V, while for the constant direct voltage $+U_7$, there applies that $U_7 = 12$ V. The voltages M_3 and M_4 have a positively directed pulse having a duration of τ which is equal to the delay times of the delay circuit $E_1 \dots E_6$ while the voltage M_5 has a negatively directed pulse. A pulse repetition period of 3τ results from the voltages M_3 , M_4 and M_5 .

The time τ indicated in FIG. 2 corresponds to the time when one of the pick-up elements TC of FIG. 1 is connected through one of the transistors $T_{10} \dots T_{10}$ to the output conductor A_{00} . For the time τ given in FIG. 2 there applies that the voltage M_3 maintains the diode D_5 conducting, the voltage M_4 maintains the transistor T_4 conducting and the voltage M_5 maintains the field effect transistor T_8 conducting. The result is that the source W_3 active as a reference voltage source provides the reference voltage of $U_8 = 8.5$ V $+ 1.5$ V $= 10$ V for the capacitor C_3 . The current derived from the input Z_0 is derived through the transistor T_4 from the capacitor C_4 while the conductance of the field effect transistor T_8 which is determined by the voltage across the capacitor C_5 provides a voltage drop across the resistor R_2 . During the next time duration τ the transistor T_3 , the field effect transistor T_7 and the diode D_7 will conduct while subsequently the field effect transistor T_6 , the diode D_6 and the transistor T_5 will conduct. Instead of using the delay circuits $E_1 \dots E_6$ the sources W_3 , W_4 and W_5 may be provided with three outputs which convey 120° phase-shifted voltages.

The result is that in a cycle of three stages the capacitor C_3 , C_4 or C_5 is charged to the reference voltage, subsequently undergoes a discharge and is then connected to the output Z_3 . Since the field effect transistors T_6 , T_7 and T_8 are provided with an insulated gate electrode, the charge of the capacitors C_3 , C_4 and C_5 upon their interconnection to the output Z_3 is not influenced. Thus the resistor R_2 is connected in the output circuit Z shown in FIG. 2 to a charge measuring circuit which comprises the transistors T_6 , T_7 and T_8 in series with the resistors R_5 , R_4 and R_3 and the source W_5 . Other embodiments of the discharge measuring circuit (T_6 , T_7 ,

T_8 , W_5) are alternatively possible. In the embodiments shown in FIG. 2 not only the leading edge slope variation is eliminated, but an output signal is obtained whose value is constant throughout the selection period.

FIGS. 3a to 3d show an embodiment of a pick-up panel shown in FIG. 1 with the pick-up elements TC integrated in a semiconductor body. FIG. 3a is an elevational view of part of the semiconductor body. FIG. 3b shows a partial cross-section of the semiconductor body taken on a line K_1 , K_2 . FIGS. 3c and 3d show transversely to the line K_1 , K_2 cross-sections which are taken on a line L_1 , L_2 and Q_1 , Q_2 . The relationship between the different crosssections is denoted by L , Q and K .

FIGS. 3a to 3d show that the semiconductor body is built up of a substrate of p-type semiconductor material on which compartments of n-type material are formed by separation diffusions of p^{++} material. In some compartments a so-called buried layer of n^+ material as commonly used for coupling purposes is provided. In the compartments islands have been formed p^+ and n^{++} material. The plus and minus notations used for the semiconductor material n and p indicates a more or less strong concentration of donors or acceptors. Different concentrations have been emphasized by means of different line types and thicknesses in FIGS. 3a to 3d. In the compartment the n-layer, the buried n^+ layer and a comb-shaped n^{++} island constitute a common collector (FIGS. 3a and 3b). A transparent insulating layer of, for example, silicon oxide not shown is provided across the semiconductor body, which layer is provided with connection apertures indicated in FIG. 3a by rectangles provided with diagonals. Electrically conducting strips of, for example, aluminum are provided on the insulating layer and the connection apertures. The strips are denoted by the references used in FIG. 1 for the conductors and connections A. In FIGS. 3b, 3c and 3d the base islands of the transistors T_{20} , T_{21} and T_{22} are denoted by b , and emitter islands are denoted by e and the collector islands denoted by c before the reference T.

The column conductors A_{01} , A_{02} etc. are formed as conducting strips while the row conductors A_{10} , A_{20} etc. are formed as a common comb-shaped collector island extending into the compartment $cT_{21} = cT_{22} = \dots$ which has a connection having a short strip, (for example A_{20} in FIGS. 3a, 3b and 3c). As compared with an embodiment using two groups of strips there is the advantage that intricate crossings requiring much space are prevented. In this case there applies that the common collector island $cT_{21} = cT_{22} = \dots$ has a larger resistance than an aluminum strip. Per pick-up element TC in a row the resistance of the collector island cT_{21} , $cT_{22} = \dots$ may be, for example, 30 Ohms. The said charge resistance for the first or the last pick-up element in a row has therefore increased by a value of $(X - 1)$ times 30 Ohms. If the comb-shaped n^{++} island in the compartments were subdivided, the resistance would be twice as large. By using the signal integration in the output circuit Z of FIG. 1, the resistance does not lead to an inadmissible distortion of the output signal. The distortion becomes manifest in a different pulse slope in the output signal. For the output circuit Z according to FIG. 2 the distortion is completely prevented by the separation between signal integration and passing on to the output Z_3 .

The base-collector capacitors $C_{11} \dots C_{YX}$ of FIG. 1 are formed in FIGS. 3b and 3d at the area of the transitions between the p^+ base island on the one hand, for example, bT_{21} and on the other hand the n^{++} island cT_{21} and the n -layer in the compartment. The capacitors $C_{11} \dots C_{YX}$ have been rendered as large as possible by the n^{++} island overlapping the base islands and a satisfactory photosensitivity is obtained by passing the light-inpermeable aluminum strip of the column conductor A_{01} over a narrow part. The unwanted base-emitter capacitance between the emitter island eT_{21} and the base island bT_{21} is as small as possible. By extending the collector island, for example cT_{22} of FIG. 3b directed beyond the base island bT_{22} to the base island bT_{21} in an overlapping manner it has been achieved that less stringent accuracy requirements are necessary for forming the base islands through diffusions. In summary the common overlapping n^{++} collector island provides the advantages of a smaller resistance, a greater photosensitive capacitance and less stringent accuracy requirements for the base diffusion.

The parasitic capacitors $C_{10} \dots C_{Y0}$ described with reference to FIG. 1 occur in an integrated form between the transition of the n -layer and the n^+ layer to the p^- substrate and of the n layer to the p^{++} separation diffusions.

The transistors $T_{10} \dots T_{Y0}$ of FIG. 1 are formed in a simple manner in their own compartment which is at right angles to the compartments of the row conductors $A_{10} \dots A_{Y0}$. The collectors cT_{10}, cT_{20} etc. are interconnected by a single aluminium strip as the output conductor A_{00} .

Although only the embodiment of the pick-up elements TC and the transistors $T_{10} \dots T_{Y0}$ is given as being integrated in a semiconductor body, the scanning generators G_Y and G_X may alternatively be integrated therein.

The integrated embodiment of the sensor shown in FIGS. 3a to 3d is an embodiment employing so-called bipolar transistors. This is especially of importance for the transistors $T_{10} \dots T_{Y0}$. In fact it has been described hereinbefore that the resistance in the charge circuit of a pick-up element TC , for example (T_{11}, C_{11}) is to be so low that the capacitor C_{11} at the end of the selection period is charged to the reference voltage. However, when the charge resistance is so large that the reference voltage is not achieved the remaining charge shortage produces a cross-over at the next selection. Since the charge resistance is also determined by the resistance of the conducting transistor $T_{10}, T_{20} \dots$ or T_{Y0} it is important to render it as low as possible. Bipolar transistors have a negligible resistance in contrast with field effect transistors, for example, MOS transistors which have a considerable resistance between the drain and source electrodes. When forming the transistors $T_{10} \dots T_{Y0}$ as field effect transistors cross-over phenomena may occur so that the bipolar construction is by far preferred.

What is claimed is:

1. A sensor provided with a pick-up panel formed with a cross-bar system of row and column conductors and pick-up elements occurring between intersections, said conductors being connected to outputs of row and column scanning generators each applying successive pulses with a reference voltage to the outputs, said panel being connected to an output circuit for applying

an output signal to an output of the sensor through a row and column selection, a plurality of row selection transistors having bases, collectors and emitters, the outputs of the row scanning generator being separately connected to the bases of said row selection transistors, the emitter of each row selection transistor being connected to a separate row conductor, each output of the row scanning generator thereby being connected to a corresponding row through the base and emitter of a corresponding row selection transistor, means for interconnecting the collectors of said row selection transistors and for connecting said interconnected collectors to the output circuit, said row scanning generator providing each row selection transistor base with a D.C. bias during the scanning of a corresponding row.

2. A sensor as claimed in claim 1, provided with pick-up elements formed with a photosensitive transistor whose emitter is connected to one of the column conductors and whose collector is connected to one of the row conductors, wherein the outputs of the column scanning generator convey a predetermined voltage cutting off the said transistors in the temporary absence of the said pulse with the reference voltage.

3. A sensor as claimed in claim 1, wherein said interconnected collectors are connected to an emitter of at least one transistor present in the output circuit, the base of said transistor being connected to a bias source and its collector being coupled to the output of the sensor.

4. A sensor as claimed in claim 3, wherein an integrator with a capacitor and a reference voltage source is provided in the output circuit between the output of the sensor and the collector of the said transistor, said integrator being connected to the pick-up elements through the selection with the row and column scanning generator.

5. A sensor as claimed in claim 4, wherein the output circuit has two integrators whose capacitors are alternately connected to successive pick-up elements or are connected to the reference voltage of the voltage source.

6. A sensor as claimed in claim 4, wherein the output circuit includes three integrators whose capacitors are connected alternately in a cycle to the reference voltage source, to one of the pick-up elements and to a charge measuring circuit connected to the output.

7. A sensor as claimed in claim 1, wherein the sensor is at least partly integrated in a semiconductor body, the rows of pick-up elements formed as transistors being provided in compartments formed by separation diffusions, the row conductor being formed as a common extending collector island in the compartment and the column conductor being provided as a conducting strip on the semiconductor body.

8. A sensor as claimed in claim 7, wherein said collector island is provided in an overlapping manner across separated base islands of the transistors in the pick-up elements.

9. A sensor as claimed in claim 7, wherein said transistors connected to the row scanning generator are formed in one compartment which is at right angles to the compartments of the rows, while the connection between the collectors is provided as a conducting strip on the semiconductor body.
